DISPOSABLE HOSPITAL GOWN

Phyllis B. Gilpin, Woodacres, Md.

Application April 2, 1951, Serial No. 218,800

1 Claim. (Cl. 2—114)

1

The invention relates to hospital garments, and more particularly to hospital garments of the disposable type.

A main object of the invention is to provide a novel and improved disposable hospital garment which is simple in construction, which is inexpensive to manufacture, which may be conveniently packaged, and which is comfortable to wear.

A further object of the invention is to provide an improved disposable hospital garment for use by medical personnel, such as surgeons and nurses, or by hospital patients, said garment being sturdy in construction, being substantially water-repellent, being readily sterilized, and being adaptable for use either in hospitals or in private practice as an economical substitute for the costly fabric gowns now used.

A still further object of the invention is to provide an improved disposable sterilized gown for use by medical personnel or patients, said gown being intended as a substitute for fabric gowns now in use and having numerous advantageous features over fabric gowns, such as being water-repellent, eliminating the need for laundering, and being very inexpensive, whereby the disposable garments may be used in war zone hospitals, on naval vessels, and in first aid stations in locations where sanitation, laundry and sterilization facilities are limited or are totally unavailable.

A still further object of the invention is to provide an improved disposable hospital gown which may be fabricated from cheap material such as paper or nonwoven fabric, which may be sterilized either prior to or subsequent to the fabrication of the garment, which involves very simple patterns for its component parts, which requires a minimum amount of handling during the fabrication thereof, which requires relatively simple machinery to construct, and which may be readily manufactured by mass production methods.

Further objects and advantages of the invention will become apparent from the following description and claim, and from the accompanying drawings, wherein:

Figure 1 is a front view of a person wearing an improved disposable surgeon's gown constructed in accordance with the present invention, a portion of the gown being shown in cross-section.

Figure 2 is a rear view of the person, showing the rear portion of the surgeon's gown of Figure 1.

Figure 3 is a front view of a nurse wearing a disposable nurse's gown constructed according to the present invention.

Figure 4 is a back view of an improved disposable patient's gown constructed according to the present invention.

Figure 5 is an enlarged cross-sectional detail

2

view taken on line 5—5 of Figure 1, showing the details of one form of cuff which may be employed on a disposable surgeon's gown according to this invention.

5 Figure 6 is a fragmentary elevational detail view, partly broken away, showing details of construction of the neck portion of a disposable gown according to the present invention.

10 Figure 7 is an enlarged fragmentary cross-sectional detail view showing an alternative cuff construction which may be employed in a disposable surgeon's gown according to the present invention.

15 Figure 8 is an enlarged cross-sectional detail view showing a modified form of waist construction which may be employed in a disposable hospital gown according to the present invention.

20 Figure 9 is an enlarged cross-sectional detail view of the waistband construction employed in the disposable gowns of Figures 1 to 3.

25 A main purpose of the present invention is to provide disposable gowns for surgeons, nurses and patients for use in operating rooms as well as for office wear, which would be usable only once and hence would not require laundering and sterilization after use, but would be thrown away. The material employed for the main portions of the gown is preferably paper or nonwoven fabric, provided with a suitable surface film to make it

30 water-repellent, yet allowing the wearer to perspire, such as "Dri-film," aluminum stearate, or a suitable plastic, either manufactured into the material or applied after manufacture. It is contemplated that the gowns will be sterilized by

35 any suitable process by the manufacturer after fabrication, and packaged in hermetically sealed containers, such as vegetable parchment envelopes, so that the gowns will be maintained in sterile condition until used. The gowns may also

40 be packaged in screw top cans and sterilized in water by heat. Thus, the gowns will be suitable for use not only in general hospitals and private medical offices but in war zone hospitals, on naval vessels, and in first aid stations where laundering and sterilizing facilities are unavailable.

45 The gowns may be treated so as to be water-repellent either over their entire surface or merely in front. The gowns are manufactured in various sizes, such as "small," "medium" and "large."

50 Referring to the drawings, and more particularly to Figures 1 and 2, 11 generally designates a surgeon's gown constructed in accordance with the present invention. The main body of the gown comprises a front section 12 and respective

55 mating rear sections 13 and 14 connected to front section 12 by shoulder seams 15 and 16, and by side seams 17 extending from beneath the armpits to the bottom edge of the gown. The seams

60 may be formed by gluing the margins of the sec-

tions together in overlapping relationship, as shown, and mechanically binding the overlapped margins by long stitches, as shown at 18. The seams may alternatively be formed by various other methods, such as by heat-sealing, employing a suitable thermoplastic sealing compound, by stitching, or by gluing, using a type of glue which would withstand sterilization. The margin of one member may be overlapped onto the margin of the other member for the width of the seam and joined by employing one of the above methods. As a further alternative, the paper or nonwoven fabric may be processed during manufacture, onto suitable forms, whereby structural seams may be eliminated.

Should the paper or nonwoven fabric employed in the main portion of the gown be relatively stiff, a softer grade of paper or nonwoven fabric may be employed as a neckpiece, as shown at 19, shaped as shown in Figures 1, 2 and 6, and secured to the top margins of the sections 12, 13 and 14 by overlapping and stitching and/or adhering, as shown in Figure 6. The neckpiece 19 is provided at its ends with integral tying strips 20, 20 for fastening the ends of the neckpiece together around the wearer's neck. The top margin of the neckpiece is formed with an inwardly folded, stitched hem 21 for wearing comfort.

The sleeves of the gown are designated respectively at 22, 22 and are formed of rectangular sections of paper or nonwoven fabric connected together at their longitudinal edges to define tubular sleeves. The top ends of the sleeves are adhered and/or stitched to the main sections of the gown at 23 in the manner above described. The lower end portion of each sleeve is formed to define a cuff 24. As shown in Figure 5, the upper margin of the cuff comprises an integral external tubular heading 25 whose inner lips are secured together by adhering and/or stitching at 26, said heading containing an elastic band 27. The lower margin of the cuff is formed with an inwardly turned hem 28 which contains an elastic band 29.

As an alternative construction, the cuff may comprise a separate tubular section 24', overlapped, adhered and/or stitched on the lower marginal portion of the sleeve, shown at 22' in Figure 7. The cuff 24' is coated with a film of high temperature-resistant rubber or elastomeric material, shown at 30, which renders the cuff substantially elastic after the elastic film 30 has been baked thereon.

Another alternative cuff may be formed by folding the cuff section into small adjacent pleats, which would be spread open to fit as the gown is put on.

Waterproofed industrial crepe which has been given an elasticizing treatment may also be used for cuffs. Price permitting, elastic webbing cuffs, such as employed in underwear, may be used.

The waistband portion of the gown comprises an integral external heading 31 formed in the manner shown in Figure 9, as by horizontally folding the garment sections at 32 and 33, overlapping the folds, and gluing or heat-sealing the overlapped folds together. A tie string or tape 34 is contained in the heading 31, the ends of the string or tape being employed to secure the waist portion of the gown behind the wearer, as shown in Figure 2.

Instead of employing continuous main body sections, the main body portion of the gown may comprise a blouse section 35 and a skirt section 36, as shown in Figure 8. The integral tubular

waist band heading, shown at 37, is formed in the lower marginal portion of the blouse section and the lower margin of said blouse section is lapped over, adhered and/or stitched on the upper marginal portion of the skirt section.

The nurse's gown, shown at 38 in Figure 3, is generally similar in construction to the surgeon's gown above described, except that the sleeves, designated at 39, 39, are of three-quarter length, 10 and are not provided with cuffs. According to the strength of the material used, the sleeves of the nurse's gown may be hemmed at their lower edges.

The patient's gown, shown at 40 in Figure 4, is 15 also generally similar to the surgeon's gown except that the waistband is omitted and the sleeves, shown at 41, 41, are of full length and are not provided with cuffs. According to the strength of the material used, the sleeves of the patient's gown may be hemmed at their lower edges.

As above mentioned, the various sections of the gown are made of paper or nonwoven fabric. The neckpiece may be of softer grade, if desired. A thin film of "Dri-film," aluminum stearate, or a 25 suitable plastic may be applied over the entire outer surface of the gown or over the front of the gown to make either the entire garment or the front of the garment substantially water-repellent.

The gowns may be packaged either in hermetically sealed sterilized envelopes, as above described, or may be packaged in screw-top sealed cans which may be sterilized in water by the application of heat.

While certain specific embodiments of improved disposable hospital gowns have been disclosed in the foregoing description, it will be understood that various modifications within the spirit of the invention may occur to those skilled in the art. Therefore it is intended that no limitations be placed on the invention except as defined by the scope of the appended claim.

What is claimed is:

A disposable hospital gown of the character described comprising a main section of flexible nonwoven fibrous material of substantial length shaped to fit substantially entirely around a person's body, said gown having shoulder portions, respective flexible sleeves connected to the opposite shoulder portions of said main section, a pair of spaced tubular headings integrally formed at the end portion of each sleeve and extending around said sleeves, respective elastic bands in the headings, whereby each pair of bands defines an elastic cuff at the end of a sleeve, a neckpiece of relatively soft material secured to the top marginal portion of said main section and formed with elongated extensions at its ends adapted to be tied together, a tubular heading integrally formed at the midportion of said main section and extending around said midportion, and a tie string in said last-named tubular heading.

PHYLLIS B. GILPIN.
